UNITED STATES PATENT OFFICE

155,609

DESIGN FOR A PORTABLE SPEAKER

Bert R. Hooks, Columbia, S. C.

Application August 3, 1948, Serial No. 147,904

Term of patent 7 years

(Cl. D26—14)

To all whom it may concern:

Be it known that I, Bert R. Hooks, a citizen of the United States, residing at Columbia, in the county of Richland and State of South Carolina, have invented a new, original, and ornamental Design for a Portable Speaker, of which the following is a specification, reference being had to the accompanying drawing, forming part thereof.

Figure 1 is a front elevational view of a portable speaker, showing my new design.

Figure 2 is a rear perspective view thereof on a reduced scale, and

Figure 3 is a cross-sectional view, taken substantially in the plane of the line 3—3 in Figure 1.

I claim:

The ornamental design for a portable speaker, as shown.

BERT R. HOOKS.
